W. S. ALLEN

GOLF CLUB

Filed March 5, 1921

Inventor
By William S. Allen,

Attorney
James H. Allen

UNITED STATES PATENT OFFICE.

WILLIAM S. ALLEN, OF CHICAGO, ILLINOIS.

GOLF CLUB.

Application filed March 5, 1921. Serial No. 449,627.

To all whom it may concern:

Be it known that I, WILLIAM S. ALLEN, a citizen of the United States, residing in Chicago, Illinois, have invented certain new and useful Improvements in Golf Clubs, of which the following, taken in connection with the drawing, is a description.

My invention has for its object the production of a golf club head designed to be used by players of the game of golf, and one which will contain all of the advantages of the present clubs and in addition thereto will have added features of improvement whereby the advantages of having the weight of the club directly back of the ball at all times will be possible.

It is also an object of my invention to provide a club which may be formed of any kind of material suitable for the purpose, such as wood, fiber, ivory, metal or the like and which is so shaped and formed that the weight necessary to drive the ball may be incorporated in the spoon or head of the club, and that the weight may be equally distributed over the club face and so arranged that the weight is brought closer to the line of control extending through the handle than is possible with clubs as now constructed.

It is also an object of my invention to provide a weight which by its own construction locks itself into the body of the club.

A further object of my invention is to construct a weight which may be varied to meet different requirements and which is easily adjustable for the purpose intended, and which is effective for both right and left hand players.

In the accompanying drawings I have illustrated what I now consider the preferred form of an embodiment of my invention although not desiring to be limited to the exact details in the matter of proportion and dimensions of the different parts.

In these drawings—

Fig. 1 is a side or rear elevation of the golf club head,

Fig. 2 is a top plan view of the same with the weight removed,

Fig. 3 is a longitudinal sectional view through the head of the club taken on line 3—3 of Figure 1 looking in the direction of the arrows,

Fig. 4 is a transverse sectional view taken on line 4—4 of Figure 2,

Fig. 5 is a side elevation of the club head

illustrating the recess adapted to receive the face-plate,

Fig. 6 is a perspective view of one of the removable weights to be placed in the club head.

Referring to the drawings A represents the head or spoon of the golf club which is formed of wood, or any other desirable material and has connection with a shaft or handle, (not here shown), but which may be of any kind now in general use. In the drawing I have shown a conventional form of head but contemplate changes in length, width and proportions to suit different individuals.

The head A is cored out or recessed as at a through the body thereof, which recess is adapted to receive the wedged weight B. This weight is formed of metal and fits the recessed portion a. The general contour of the body portion of the weight B is practically semi-cylindrical in one direction and wedge shaped in the other, and is provided with a recess or cavity b therein which is adapted to receive a plurality of removable members a' varying in weight, one or more of which may be placed in the cavity depending upon the weight desired. A screw a² or other fastening means extends through a cover plate a³ and the weight members a', and engages the bottom of the weight body B to hold said pieces firmly in place.

The upper edges of the body of the weight B are provided with ribs or beads b²—b², which engage with correspondingly shaped grooves b³—b³ formed in the head A. These ribs b² are preferably slightly tapered from end to end thereof by means of which a locking wedging engagement is formed with the correspondingly shaped grooves or channels.

C is the neck portion of the weight member B which may be formed longer or shorter as desired to bring the weight B near the center of control of the club, the center of control being represented by a line passing through the center of the handle and extending through the club head A to the end thereof.

The neck portion C of the weight widens toward the surface of the club and extends in a curved direction from each side of said neck to an engaging rib c—c on each side thereof, and forms the exposed face C' of the weight conforming to the contour of the

head of the club A. The ribbed members $c-c$ extend parallel with the ribbed members b^2-b^2 and are likewise tapered from end to end to lock the parts into the correspondingly shaped channels b^3-b^3 and b^4-b^4 receiving them.

The body portion A of the club is recessed upon one side thereof as at D. D' is a face plate formed of any material suitable for the purpose, and which has projecting from one side thereof an integrally formed member d which fits the recess D. When it is desired to lighten the weight of the face plate the projecting portion thereof d may be cut or 15 hollowed out and filled with wood or other lighter weight material.

Extending through the body portion A and the projecting member d are one or more apertures e—e, the diameter of which is 20 slightly tapered to provide a tight fitting wedging locking connection when the pins e'—e' are driven therethrough.

All of the parts are built to very accurate measurements so that when assembled the 25 head forms a very compact close fitting construction, one in which all of the parts are interlocked with their contiguous members by forming the wedging engagement with the different parts thereof as heretofore explained. A retaining plate E fits into a corresponding countersunk portion in the bottom of the club and is screwed or otherwise fixedly secured to the body A.

It will be observed that all the metal parts 30 are either tapered or wedge shaped as previously explained, the exposed surface C' fitting into the body A in an opening which is slightly narrower at the top than at the bottom thereof. The weight B can only be 35 inserted in the body A through the bottom.

The pins e'—e' can only be inserted through the bottom of the body portion; the beads b^2-b^2 , $c-c$, are also tapered from end to end to form a tight, wedging connection for the weight within the cavity designed for it. The engaging curved surfaces $i-i$ of the weight body B, the body of the club A, with the curved surfaces $i'-i'$, between the foot of said weight and the 45 body portion of the weight, lock closely around the parts of the material forming the body portion A, continuous thereto, thus providing a very secure and compact structure when assembled; one which will at all 50 times hold the parts in fixed position regardless of the usage given the club in playing the game.

The provision of the removable weights a' 55 I consider one of the important features of my invention, inasmuch as the weight behind the striking point on the ball is of importance in directing the successful manipulation of the club.

As shown in Figure 6 the removable 60 weights are constructed of a size suitable

to snugly fit within the recess or cavity provided for them in the weight body B. I contemplate the use of one or more of these weights as desired by the user. Ordinarily the weights are formed of lead but for the purpose of varying the weight I contemplate forming one end of lead and the other of aluminum or some other lighter weight material, or one end of the weight may be removed entirely for the purpose of making it lighter. In the latter case I will have provided more weight above the center of the ball where the strike is made, the effect being to direct the ball in a downward line of travel. If the weights are changed to occupy the lower half of the cavity in the weight body, I will have provided more weight beneath the center of the ball when the strike is made, the effect being to direct the ball in an upward line of travel. When it is desired to use the club with full weight as shown in Figure 3 of the drawing, there is an equal distribution of weight above and below the center of the ball thereby causing the ball when struck to travel in a horizontal direction. Thus it will be understood that by the variation in the weight of the club head, and the position of said weights in the club, a player will, to a great extent, be able to control the line of direction the ball will travel.

I claim—

1. A golf club head having a tapered recess extending through said club and to the rear thereof, a tapered weight extending through said recess, means for effecting an interlocking wedging engagement therewith, and means for securing said weight in said recess. 100

2. A golf club head having an irregular shaped tapered recess extending from the top to the bottom of the club and to the rear thereof, a weight fitting said irregularly shaped recess and having interlocking wedging engagement therewith, and means for securing the weight in the recess. 105

3. A golf club head having a vertical recess extending through the body and to the rear thereof, a weight fitting in said recess and having means thereon for engaging channels provided in the body and forming an interlocking engagement therewith, the body of said weight being chambered, a plurality of removable members fixedly secured within said chamber, and means for securing the weight in the recess. 110

4. In a golf club head, the combination of the body of the club having an opening extending vertically and transversely through one side and the rear thereof, a weight fitting within said opening, said weight provided with a plurality of engaging members fitting channels in the body portion and forming locking engagement therewith, and means retaining said weight in place. 115

5. In a golf club head, the combination of the body portion of the club having an irregular shaped vertical opening therethrough which extends to the rear of the club head, said opening being tapered from the bottom to the top thereof, a weight corresponding in shape with said opening and fitting therein with a wedging engagement, the edges of said weight having beads formed thereon which enter corresponding channels and form an interlocking engagement with the club head, and means securing said weight in the opening. 60
10. In a golf club head, the combination of a body portion having an opening therethrough, a weight conforming to the contour of said opening and having means formed integrally therewith for effecting an interlocking engagement with the body of the club head, said weight having a neck portion provided with shoulders extending from the sides thereof and widening to present a metal surface at the rear of the club, and means secured to said club head for retaining the weight in said opening. 65
15. In a golf club head, the combination of the body portion of the club having an irregular shaped vertical opening therethrough which extends to the rear of the club head, a weight conforming in contour to said opening and having means for effecting an interlocking engagement therewith, said weight having a chamber therein to receive a plurality of removable members, means for securing said removable members in said chamber, and a shoe fitting 70
20. a countersunk recess in the bottom of the club and secured thereto. 75
25. In a golf club head, the combination of a body portion having an irregular shaped vertical opening therethrough which extends to the rear of the club, a weight conforming to the shape of said opening and having interlocking engagement therewith, said weight having a chamber therein, a variable number of removable members 80
30. fixedly secured in said chamber, means formed integrally with said weight for interlocking it with channels formed in the club body, and a sole plate secured to said club. 85
35. 8. In a golf club head, the combination of a body portion having an irregular shaped opening therethrough, and a weight conforming to the shape of said opening, said weight formed of a plurality of members fixedly secured together and adapted 90
40. to be varied in number, beads formed on different edges of said weight, said beads engaging channels in the body of the club and having locking engagement therewith, and means retaining said weight in place. 95
45. 9. In a golf club head, the combination of a body portion having an opening therethrough, extending from the top to the bottom of the head and to the rear thereof, a weight conforming to the shape of said 100
50. 55. 103
- opening, means formed integrally with said weight for effecting an interlocking engagement with channels formed in the body of the club head, a shoe fitting a countersunk recess in the bottom of the club and secured thereto to hold the weight in the recess, and a face plate attached to the side of the club head opposite the weight.
11. In a golf club head, the combination of a body portion having an opening therethrough, a weight conforming to the shape of said opening and having interlocking engagement therewith and extending to the edge of the club at the rear thereof, a recess formed in the club at the opposite side thereof, a face plate extending over said recess and having a projection fitting therein, means for locking said face plate in fixed position, and a shoe covering the bottom of said club and retaining the weight therein. 85
12. A golf club head having a vertical opening through the body thereof, said opening extending transversely to the rear of the club, a weight extending through said opening and having means for effecting interlocking engagement with channels formed in the club body, a face plate on one side of said club, and means for securing said plate to the club body. 90
13. A golf club head having an irregularly shaped recess extending from top to bottom and to the rear thereof, a weight conforming to the shape of said recess and positioned in said recess and having interlocking engagement with the wall thereof, a face plate provided with a projection extending into a recess formed in the club, and engaging pins extending through said projection and the club body to secure said face plate in fixed positions. 100
- In testimony whereof I have signed this specification.

WILLIAM S. ALLEN.
